(57) **CLAIM**

The ornamental design for a dog training remote control, as shown and described.

DESCRIPTION

FIG. 1 is a front, left, top perspective view of a dog training remote control showing my new design;

FIG. 2 is a back, right, bottom perspective view thereof;

FIG. 3 is a front elevation view thereof;

FIG. 4 is a back elevation view thereof;

FIG. 5 is a left elevation view thereof;

FIG. 6 is a right elevation view thereof;

FIG. 7 is a top plan view thereof; and,

FIG. 8 is a bottom plan view thereof.

In the drawings, the broken lines depict portions of the dog training remote control that form no part of the claimed design.
